FIREARM

Heinrich Wimmersperg, Vienna, Austria

Application January 9, 1937, Serial No. 119,784
In Austria January 22, 1936

8 Claims. (Cl. 89—2)

This invention relates to automatically repeating fire-arms, more particularly of the double-barrel type.

Attempts have been made heretofore to design automatically repeating fire-arms for rapid firing using two parallel barrel systems coupled together in such a manner that they will fire alternately. In the gas pressure loader type of fire-arm it has been proposed to couple the two gas impelled pistons by means of a pinion so that the backward movement of the one brought about the forward movement of the other. In the case of systems with short recoil movement it has been proposed for example to control the two breeches by means of a double-armed lever in such a manner that the recoil movement of the one positively effects the forward movement of the other. Firearms built along these lines heretofore were very complicated in construction and did not fire more rapidly than the ordinary type. The main reason for this failure was that in the double system guns more than twice the previous mass had to be accelerated, with the result that the recoil velocity was halved. Total performance thus remained the same as that of the usual single-barrel fire-arms, while the complete weapon was more than twice as heavy, far more complicated, and very considerably more expensive than the simple type of fire-arms. The suggestions to modify gas pressure loaders, by connecting two barrels in such a way that gases diverted from the one barrel actuate the gas piston rod and the breech of the other barrel did not produce any increase in the rate of firing, since during the breech movement of the one barrel the other was out of action and consequently fired merely at half speed.

According to the present invention at least one of the two barrels is longitudinally movable and adapted, during its forward movement, to push a cartridge into the other barrel and fire the same and, during its recoil, to eject the empty cartridge case from said other barrel while simultaneously loading itself with a fresh cartridge. The latter is fired when the barrel in question reaches its rearmost position, whereupon the empty cartridge case is discharged from this barrel. Thus, alternating firing of the two barrels is obtained without the use of any control member.

There are various ways of providing for automatic repetition in a fire-arm of this description. For example, the forward motion loading barrel which is movable may be forced back by gases diverted from the other barrel, which is fixedly mounted, the movable barrel being brought for-

ward again by means of a closing spring. Or alternately, the forward motion loader barrel is forced back by the recoil of the other barrel and brought forward again by a spring. It will be clear that other types of actions are conceivable without departing from the main principle underlying the invention which may be summed up as follows: "Firing off one cartridge when the first barrel is in the rearmost position, and firing off the next cartridge, through the second barrel, when the first barrel is in its extreme forward position." The first-mentioned type of action admits of very simple structural embodiment, since the stationary barrel may be utilized to guide the moving barrel, so that no guiding tube is required for a gas impelled piston need be provided, and the moving barrel itself serves as gas piston. Thus, by addition of a breech for the moving barrel this system may be adapted for alternate firing, both barrels being equipped with rigid locking, and no controlling mechanism being required. On account of the slight masses to be accelerated, this system develops a very high rate of firing, and combines simplicity of construction with light weight. It is also possible to do without the breech either for the movable or the stationary barrel, or for both, in cases in which rigid locking of the barrels is not necessary.

Forms of construction embodying the invention are shown, by way of example, in the accompanying drawings, in which:

Fig. 1 is a side elevation, partly in longitudinal section, Fig. 2 is of a form of construction according to the present invention including a cartridge magazine feed; a section taken on the line *a—a* of Fig. 1. The phase shown in these two figures is the forward position of the movable barrel.

Fig. 3 shows a form of construction for use with a double-row cartridge belt; Fig. 4 is a side elevation on the line *b—b* of Fig. 3, and Fig. 5 a section taken on the line *a—a* of Fig. 3, the breech of the moving barrel being removed for the sake of clarity.

Figs. 6 to 11 show a further form of construction in which the ejector serves at the same time for the forward feeding of the cartridge carrier.

Referring more particularly to Figs. 1 and 2, the barrel 3 is rigidly mounted in the housing 1 and provided, near the muzzle, with the gas chamber 3g. The moving barrel 2 is guided in this chamber and in the housing 1. At its forward part this barrel is equipped with the annular gas piston 2g and at its rearward part with a long extension 2a to which there is attached the pusher rib 2e (Fig. 2) together with the ejector

2w, these latter elements being adapted in part to traverse the breech block 5. The striking pin 6 and the cartridge extractor 7 are mounted in the breech block 5. The latter is capable of longitudinal movement, and, in its foremost position, of a slight pivotal movement to which it is constrained by the engagement of the claw 5k in suitably shaped grooves in the housing 1. The claw 2k on the barrel extension co-acts with the lower breech block 9 and constrains the same, in its foremost position, to hook in behind the arresting shoulder 17. The striking pin 8 is adapted to lock itself to the barrel extension 2a. The cartridge feed is the same for both barrels, and is effected from a magazine associated with each barrel and placed at the right-hand side thereof as seen in plan view from above (Fig. 2). Each magazine consists of the box 10, the feed piece 12, and the spring 11.

20 At the beginning, the firearm is in the position in which the moving barrel 2 is at back dead centre. The top breech block is then connected and locked to its barrel, since the claw 5k depresses the rear end of the breech. The barrel 2 will then not be loaded. The lower breech 9 is thus likewise in its rearmost position. As soon as the moving barrel is released the closing spring 4 draws it forward taking the upper breech along with it until this breech is unlocked by engagement of the claw 5k in the casing, and comes to a standstill. The barrel 2 travels on, and its pusher rib 2e engages the rear end of a cartridge from the magazine, in known manner, and carries it along in front of it. In the meantime the lower breech block 9 has also been urged forward and in its movement picks up a cartridge from its magazine and thrusts the same into the fixed barrel 3. Finally, the breech block 9 is caused to become locked relatively to the housing, and the cartridge is fired off by the striking pin. The projectile travels past the gas port, whereupon the discharged gases impact against the piston 2g and move the movable barrel 2 back. Barrel 2 travels back past the inserted cartridge which at this moment is still travelling forwards, encounters the upper breech block 5, locks itself to it, and takes it back with it. At the commencement of the backward movement of the barrel 2 the lower breech block 9 is unlocked and carried back, with the result that the empty cartridge-shell is extracted and ejected in the usual manner. As the barrel 2 reaches its rearmost position the striking pin 6 is arrested by the rear wall of the housing and fires off the upper cartridge.

50 As soon as the recoil in this barrel has abated the closing spring 4 draws the barrel 2 forwards, and in the course of this forward movement of the barrel the upper breech block unlocks itself again and comes to a standstill. The pusher rib 2a travels on with the barrel, and the ejector 2w ejects the empty cartridge-shell. By the introduction and firing off of a fresh cartridge in the lower barrel 3 the described cycle of operations is repeated. The two barrels may be disposed very closely together, and in this manner it becomes possible to combine the two magazines in a single unit. The changing of magazines is thereby greatly facilitated.

70 The cartridges may also be fed with the aid of belts or metal bands. In order to avoid the necessity for using two separate belts there may be used either an ordinary single-row belt with dual-stage feeding through the fire-arm or a two-row belt with single-stage feeding.

75 A form of construction of fire-arm in accord-

ance with the invention using a two-row cartridge belt is shown in Figs. 3 to 5 of the drawings.

Referring to these figures each pair of cartridges is disposed, one behind the other, in a semi-cylindrical element of the chain or belt 26 and held therein by means of spring clips 26. The individual elements of the carrier are articulately connected together by means of pins 27. The bent-up tongues 26z prevent the cartridges in row II from touching with their tips the cases 10 of the cartridges in row I. The apertures 26f in the elements of the cartridge carrier allow the ejector 17 to enter. This latter is pivoted about the axis 18 and has mounted upon the axle 16 the pawl 15, both being pressed upon by a spring 19. The chain of cartridges travels in a passage-way provided in the housing 1, and is prevented from slipping back by the ratchet pawl 25. The feed movement is imparted by a sliding member 20 which is mounted in the housing 1 slidable in a direction at right angles to the axis of the barrel. Mid-way in its length this member is provided with a stud 20z which engages in the groove 2n in the barrel extension 2a. At the lower end the feed pawl 21 is rotatably mounted about the axis 25 22, and is actuated by the spring 23. The restoring spring 4 presses against the barrel extension 2a in the bore of which it is guided. The barrel extension is equipped with the pusher rib 2e with the nose 2a and the ejector 2w. The moving 30 mechanism and the breech mechanism correspond to the same parts in the form of construction shown in Figs. 1 and 2. Behind the breech 5 there is provided in the present form of construction a buffer 13 with a buffer spring 14. 35

When the trigger, which is not shown in the drawings, is pulled, the restoring spring 4 draws the barrel 2 forwardly from its rearmost position. The breech block 5 is unlocked and fixed, and the empty cartridge shell ejected from the 40 barrel 2 by the ejector 2w. The breech block 9 then thrusts a cartridge from the row I out of the cartridge carrier into the barrel 3. This phase of the cycle is shown in Fig. 3. The breech block then becomes locked with the casing, subsequently the cartridge in the barrel is fired off, and the gases thereby evolved force the barrel 2 back as already explained. During the forward movement of the barrel the pawl 15 is swung out and can drop into engagement behind 50 the extension 2a when the moving barrel 2 is in its foremost position. On the backward movement of this barrel the pawl 15 is pressed upwards and constrains the ejector 17 to push the next cartridge in row II out of the cartridge 55 carrier into the path of the barrel 2, the cartridge being prevented from becoming excessively deflected, by the nose 2s. The proper positioning of the cartridge for its insertion into the barrel is thus ensured by the clinching action 60 of the adjoining parts. The barrel 2 then slides past the cartridge the end of which slips clear of the edge of the casing as soon as nose 2s permits and becomes supported against the breech block 5. The pawl 15 is again released by the 65 barrel extension 2a, so that the ejector 17 is brought out of the cartridge carrier. The stud 20z on the sliding member is guided by the groove 2n, with the result that the feed latch 21 feeds the cartridge carrier forward to the extent of 70 one element. The ratchet pawl 25 prevents the cartridge carrier from slipping back. The barrel becomes locked to the breech block 5, and the striking pin 6 encounters the buffer 13 and fires off the cartridge. In the further course of the 75

forward movement of the barrel 2 the groove 2n depresses the sliding member again, with the result that the feed latch 21 can come into engagement behind the next element of the cartridge carrier. The thrusting of the cartridge into the barrel 2 is thus effected in this case directly by the backward movement of this barrel, and there is no need for a preparatory setting or positioning of the cartridge during the forward movement of the barrel as in the case of the first described form of construction. It is of course perfectly possible to feed barrel 2 from row I and barrel 3 from row II without in any way departing from the principle of the invention.

Figs. 6 to 11 of the drawings show a form of construction of the fire-arm according to the invention in which the ejector serves at the same time for the feeding forward of the cartridge carrier. The difficulties encountered owing to the necessity of rapidly withdrawing the ejecting member from the gap in the cartridge carrier are avoided, while at the same time a very considerable simplification of the design as a whole is rendered possible.

Broadly, this result is achieved in accordance with the invention by providing, for the purpose of feeding the cartridge carrier forward, a preferably pivoted member which is movable in one plane and also transversely thereto, the movement of which member may also be utilized for setting or adjusting the cartridge in the proper loading position. An advantage of this arrangement according to the invention thus resides in the fact that the said member is capable of effecting both the feeding forward of the cartridge carrier and also the bringing into position of the cartridges, so that the use of a separate conveyor shoe or the like can be dispensed with. Furthermore, in consequence of the possibility thus provided of using the feed latch on this member as an ejector element, this latch element may be arranged to remain within the cartridge carrier throughout the entire feed cycle without causing any trouble. A further advantage resides in the fact that this construction makes it possible to dispense with all pawls and moving axles, so that the member provided for effecting the feeding forward and the actual positioning of the cartridge may be formed by a single sturdy and resistant part of the fire-arm.

A constructional example of this form of the invention is shown in the drawings, Fig. 6 being an inverted plan view of the conveyor feeder, the cartridge carrier being omitted for the sake of clarity, and Fig. 7 a section on the line a—a of Fig. 6. Fig. 8 is a separate elevation of the feeding and positioning member proper, as seen from beneath, and Fig. 9 an enlarged section on the line d—d of Fig. 8. Fig. 10 is a section on an enlarged scale taken through the central bearing of the feed member, and Fig. 11 an inverted plan view of the central bearing shown in Fig. 10.

Referring to these figures, 31 denotes the movable barrel corresponding to the barrel 2 in the form of construction shown in Figs. 1 to 5, which is moved over and past the cartridge 38 which is held in the cartridge carrier 37 by spring clamps, ready to be fed to the barrel (see Fig. 7). The barrel 31 is permanently connected to a barrel extension 32. 33 denotes the member provided for effecting the forward feeding movement of the cartridge carrier, this member being also employed in the present form of construction for

effecting the positioning of the cartridge in proper position for charging. This member 33 is rotatably and pivotally mounted in the housing 34, for which purpose it is fitted on a pivot pin 34a on the housing 34 (Fig. 7) and guided with its transverse arms 33qu in arcuate grooves 34/ in the housing. This manner of support enables the member 33 in the first place to carry out a rotary movement through the angle β , corresponding to the feed movement of the cartridge carrier 37. In order to enable the member 33 to carry out a rocking (ejecting) movement its central bearing is provided not only with one cylindrical bore (axis I) corresponding to the journal pin 34a, but also with a second bore of the same diameter as the first and inclined at an angle thereto, so that the axis (II) of the second bore intersects with the axis I of the first bore (see Fig. 10). The inner surfaces thus represent four semi-cylindrical surfaces separated by two double triangles. To admit of the tilting movement through the angle α (Fig. 7), the ends of the transverse arms 33qu must also be correspondingly bevelled off at the same angle α , as shown in Fig. 9. The member 33 thus can move freely in two directions. Twisting moments in the third plane at right angles to the direction of the barrel are taken up by the two transverse arms. 33z (Figs. 7 and 8) is a thrusting catch on the member 33, which effects both the feeding forward of the cartridge carrier, the ejecting of the cartridges from the carrier, and the feeding of the cartridges in position for the loading aperture 32o, for which purpose this thrusting catch 33z engages through an aperture 37o in the cartridge carrier 37. A feed catch 33s likewise provided on the member 33 extends, in the position of rest, into a cam groove in the barrel extension 32. This groove is partly in the form of a through slot, the remainder being shallower. The shoulder z of the groove serves for the positioning movement, while the part s of the groove serves for the forward feeding movement. At h the deeply excavated part begins again, and at r the cam groove for the restoring movement. A spring 35 keeps the feed catch 33s constantly pressed against the cam groove, by means of the pin 36.

As soon as the barrel begins to move backwards the feed catch 33s encounters the beginning z of the shallower part of the groove. The member is tilted through the angle and pushes the cartridge 38 out of the spring clamps on the cartridge carrier 37 into the loading aperture 32o in the barrel extension, so that in its further rearward movement the barrel may travel over and past the cartridge. This constitutes the cartridge positioning stage. The curved portion s of the cam groove then causes the member 33 to carry out its rotary movement through the angle β . The thrusting catch 33z remained all this time in engagement with the aperture 37o in the cartridge carrier. The cartridge carrier has therefore been carried along with the other moving parts and thereby feed forward. As soon as the part h of the curved cam groove takes effect the feed catch 33s drops into the slotted portion of the groove, and the engaging catch 33z is brought out of engagement with the cartridge carrier. The returning curve r can then bring the member 33 back again into the initial position. A pawl prevents the slipping back of the cartridge carrier in known manner.

The assembling of the above described parts is simple: a member 33 is placed in a position

turned too far off and then fitted on to the pin 34a, the transverse arms 33q being inserted in the arcuate grooves 34f in the housing 34. The cam groove may be provided in any part which travels through a sufficient distance in the course of the loading movement.

If the cartridge in the movable barrel is fired off by impact against a non-yielding wall the barrel is pressed against this wall by the recoil setting in immediately after expansion of the gases generated by the discharge and lasting until the restoring spring is able to overcome the counter pressure and bring the barrel forward again. The time required for the complete cycle is somewhat lengthened in this case. Figs. 1 and 2 show a form of construction of this type.

Figs. 3 to 5 show a different type in which the cartridge in the moving barrel is fired off before the rearmost position is attained, by impact against a yielding buffer. The recoil at once set up accelerates the backward movement of the barrel, and this very considerably increased recoil energy is stored up in the very powerful buffer spring which, as far as possible, should be of non-damping character. After expansion of the explosion gases the spring buffer imparts to the barrel an extremely powerful initial urge forward to which there is added, as in the previous form of construction, the action of the restoring spring. The recoil energy of the barrel 2 is thus made use of to accelerate the forward movement. This results in a very considerable reduction in the time required for the forward movement, and with it an increase in the rate of firing. It will be clear that the firing operation may be effected in any other suitable manner before attainment of the rearmost position of the moving barrel. The essential point is that the energy of the recoil shall not be destroyed but harnessed for the purpose of the forward movement of the barrel.

Apart from a stand-still due to lack of ammunition, the trigger pawl arrests the moving barrel in its rearmost position after each interruption in firing. In order to avoid firing through the moving barrel when repeating is effected by hand it is merely necessary to ensure that the striking pin is not actuated in this case, for example by limiting the backward movement or in any other manner. In the case of magazine loading it is also advisable to place the loading knob in such a position that it can be actuated only after the magazine has been detached.

I claim:

1. A unitary fire-arm, comprising a first barrel, a second barrel, means to move said second barrel in a forward direction beyond its firing position after each firing thereof, loading means for loading said second barrel in a position different from its firing position, loading means for loading said first barrel while said second barrel is in a position different from its foremost position, breech mechanisms for both barrels, the breech mechanism for the second barrel being arranged in the rear portion of the path of the second bar-

rel, means associated with the second barrel adapted upon forward movement of the same to bring the breech mechanism of the first barrel into its operative position, means for firing the first barrel when the second barrel is in approximately its foremost position, and means for firing the second barrel when this barrel is in approximately its rearmost position.

2. A fire arm as claimed in claim 1 in which said first barrel is stationary.

3. A firearm as claimed in claim 1, in which said first barrel is provided near its forward end with a passage for discharging gases and for reversing the direction of said discharge gases, said firearm comprising further a spring supporting said second barrel, the latter including means against which said gases are directed to displace the second barrel in rearward direction against the action of said supporting spring.

4. A firearm as claimed in claim 1, including a buffer disposed at the rearward end of said second barrel.

5. A firearm as claimed in claim 1, comprising further receiving means for a cartridge belt, said means being arranged to accommodate two cartridges disposed in longitudinal adjacency.

6. A firearm as claimed in claim 1, comprising further receiving means for a cartridge belt, each of said loading means including a lever movable in the direction of the cartridge transport and in a direction perpendicular thereto, said lever being adapted to advance the cartridge belt step by step and to insert successive cartridges into the loading opening of the coordinated barrel.

7. A firearm as claimed in claim 1, comprising further receiving means for a cartridge belt and a movable member having a slot therein, each of said loading means including a spring supported lever movable in the direction of the cartridge transport and in a direction perpendicular thereto, said lever being adapted to advance the cartridge belt step by step and to insert successive cartridges into the loading opening of the coordinated barrel, and carrying a sliding member in engagement with said slot, the latter being adapted to impart to said lever an oscillating motion parallel to the cartridge transport movement and having a curved portion shaped and dimensioned to hold said lever in rigid engagement with the cartridge belt.

8. A firearm as claimed in claim 1, comprising further receiving means for a cartridge belt, a movable member, studs, and stationary guide means, each of said loading means including a lever mounted on one of said studs to be movable in a direction perpendicular thereto and operated by said movable member, said lever having laterally extending arms guided by said stationary guide means so as to advance the cartridge belt step by step and insert successive cartridges into the loading opening of the coordinated barrel.

HEINRICH WIMMERSPERG.
